SLIDE FOR MULTIPLE FASTENERS

Martin Winterhalter, Morcote-Castello, near
Lugano, Switzerland

Application March 22, 1941, Serial No. 384,707

14 Claims. (Cl. 24—205.5)

My invention, which relates to slide operated multiple fasteners and has among its objects the provision of an improved handle and locking means for the slide, will be best understood from the following description when read in the light of the accompanying drawings of several embodiments of the invention selected for illustrative purposes, while the scope of the invention will be more particularly pointed out in the appended claims.

In the drawings—

Fig. 1 is a plan of a multiple fastener;

Fig. 2 is a section on the line 2—2 of Fig. 1, with parts in elevation;

Fig. 3 is a section, corresponding to Fig. 2, with the parts in a different operative position;

Figs. 4, 5, 6 and 7 are diagrams illustrating the operation of the handle member of the slide of Figs. 1 and 2;

Fig. 8 is a plan of a modified form of handle;

Fig. 9 shows a further modified form of handle with its parts in the position assumed when removed from assembled relation with the slide, this figure corresponding to a section on the line 2—2 of Fig. 1 and 9—9 of Fig. 8, with parts in elevation;

Fig. 10 is a fragment of the slide and assembled handle according to Fig. 9, corresponding to a section on the line 2—2 of Fig. 1;

Fig. 11 is a section on the line 11—11 of Fig. 1;

Fig. 12 is a plan of a further modified form of slide and assembled fastener;

Figs. 13, 14, 15 and 16 are sections on the lines 13—13, 14—14, 15—15 and 16—16 of Fig. 12;

Fig. 17 is a perspective of a detail employed in the construction according to Figs. 12 to 16; and

Fig. 18 illustrates a still further modified form of slide and assembled fastener.

Referring to the drawings, which for convenience of illustration shows the device on a much enlarged scale, the multiple fastener comprises a series of spaced cooperating fastener elements 1 of any usual or suitable kind secured to the edge portions of the webs 3.

The slide body 5, which may be of metal or molded material corresponding to the material of the fastener elements, may, as usual, be moved in one direction to cause the fastener elements on the two webs to engage so as to "close" the fastener, and may be moved in the opposite direction to cause the fastener elements to disengage so as to "open" the fastener. The slide body, like the fastener elements, may in its general aspects be of any suitable or convenient construction.

As shown in Figs. 1 and 2, the improved slide

body is provided on its exposed face with a rib 7. The rib illustrated is formed with a transverse opening having the opposite end walls 9 and 11, an outer wall 13, and an inner wall 15 formed by the adjacent exposed face of the slide body.

For moving the slide body in each of opposite directions the same is provided with a handle, preferably formed of a bent wire to provide opposite legs 17 and 19. The end portion of the leg 17, as shown, has a portion 21 extending transversely of the slide body through the opening in the rib 7 of the slide body, while the leg 19 has a corresponding portion 23 also extending through this opening. The free end part of the portion 21 of the leg 17, as illustrated, is bent to form a portion 25 extending toward the free end of a handle, this portion 25 being bent to provide a laterally extending pin 27 adapted to project through an opening 29 in the slide body so as to project into the spaces between adjacent fastener elements 1, as shown in Fig. 2.

In the above construction the handle may be swung about the portions 21 and 23 thereof as a pivot to retract the locking member constituted by the pin 27 from engagement with the fastener elements so that the slide body may be moved in either of opposite directions to open or close the fastener. It will be observed that when the parts are in the position shown by Fig. 2 the slide body cannot move in fastener opening direction as any tendency for it to do so will be prevented by the pin. As the pivot for the handle constituted by the portions 21 and 23 thereof is above the pin in the position of parts shown by Fig. 2 any tendency of the slide body to move in fastener opening direction will cause the pin to be urged into locking position when it is contacted by the lowermost fastener element of the pair of fastener elements between which it lies. Accidental movement of the slide body in fastener closing direction would not be prevented with the parts in the position shown by Fig. 2, but it is not necessary ordinarily to prevent such movement.

It will be observed that the size of the opening in the rib 7 in which the handle is pivoted provides a certain amount of lost motion between the handle and the slide body longitudinally of the latter, which arrangement is preferable to enable the locking pin 27 more readily to enter a space between adjacent fastener elements. In this modification of the invention, because the fastener is commonly positioned vertically in a garment, the wall 13 of the opening in the rib 7 is preferably inclined to make the lower por-

tion of the opening, as viewed in Fig. 2, of such dimension transverse to the direction of movement of the slide as will insure the pin being held in locking engagement with the fastener elements when the parts are in the position shown by Fig. 2.

Referring to the diagrams shown by Figs. 4, 5, 6 and 7, it will be observed that when the handle is swung from its position shown by Fig. 4, which corresponds to its position shown by Fig. 2, to that shown by Fig. 5, further swinging of the handle to position it to move the fastener in closing direction tends to be prevented by the portion 23 of the handle contacting the outer wall 13 of the opening in the rib 7 of the slide, the portion 21 of the handle under these conditions contacting the walls 9 and 15 of the opening. However, further movement of the handle progressively into its position shown by Figs. 6 and 7 will cause relative movement between the relatively resilient legs 17 of the handle, this movement gradually increasing as the handle is moved from its position shown by Fig. 5 to those of Figs. 6 and 7. This relative movement between the legs of the handle, resulting in the leg 19 swinging a greater angular distance than the leg 17, causes the handle when released, say after the fastener is closed with the handle in the position shown by Fig. 7, to snap back and move into its position shown by Fig. 4, in which position the slide lock is engaged.

The wire of which the handle is formed is preferably of such length as to permit the desired degree of relative resiliency between the legs, and is bent, as shown in Fig. 1, for example, to make it of convenient shape and size. This result may be secured by bending the wire into various other shapes, for example that shown by Fig. 8, in which the legs 31 and 33, corresponding to the legs 17 and 19 of the handle of Fig. 1, have a sinuous shape. Preferably, but not necessarily, the two legs are connected by a bridge piece 35 to prevent accidental spreading of the legs. Preferably the bridge piece is loosely connected to the legs 19, as clearly indicated in Fig. 11. As so constructed the legs may be sprung sufficiently to permit the portions 21 and 23 of the prefabricated handle to be inserted in the opening in the rib 7.

It will be observed in the modifications above described that the handle can be moved from its position shown by Fig. 4 to that shown by Fig. 5 before the relative movement between the relative resilient legs 17 and 19 occurs. In other words, when so constructed the normal position of the handle is a position in which the handle has considerable lost angular motion. The angle through which the handle may be turned from its position shown in Fig. 2 before distortion occurs between the legs to cause it to be urged back to its normal position may be varied by increasing or decreasing the distance between the walls 13 and 15 of the opening, as will be obvious from Fig. 5, and in many instances it has been found that satisfactory results will be secured when the portion 23 of the handle does not contact the wall 13 until the handle has been swung from its position shown in Fig. 2 about 30 to 45 degrees or other angle considerably less than 90 degrees.

However, to adapt the slide to any situation, say one in which it is moved horizontally, or moved vertically upward to open the fastener, and to cause the handle to be normally maintained in its position shown by Fig. 2, either the

handle shown by Fig. 1 or that shown by Fig. 8 may be formed to have the shape indicated by Fig. 9 before the portions 21 and 23 are inserted in the opening of the rib 7. As shown in Fig. 9, the two legs 37 and 39, corresponding to the legs 17 and 19 of Fig. 1, are so formed that they are at an angle to each other before the portions 21 and 23 thereof are inserted in the opening in the rib 7 of the slide body. When inserted in that opening the parts assume the position shown in Fig. 10, in which position the portion 23 of the leg 37 yieldingly bears against the outer wall 41 of the opening in the rib and the portion 21 of the leg 39 yieldingly against the opposite wall 43 of the opening. Hence the leg 37 acts as a spring to turn the handle around the portion 21 thereof as a pivot, resiliently to hold the handle in the position shown by Fig. 10. In other words, the handle when so constructed has a normal position in which it has no lost angular motion. When the handle according to Fig. 10 is swung to disengage the lock and enable the operator to pull the slide in fastener closing direction the portions 21 and 23 of the handle will move to the upper end of the opening, as shown in Fig. 10, and will coat with the walls of that opening, in exactly the same way as the handle according to Figs. 1 and 2 coats with the walls of the opening shown in Figs. 5, 6 and 7, to cause the leg 31 of the handle of Fig. 10 to swing a lesser distance than the leg 39 thereof and distort the handle out of its position shown in Fig. 10, so that when the operator releases the handle, say when it is in the position corresponding to Fig. 7, it will snap back into its position shown by Fig. 10.

The length of the wire forming the handle and the resiliency of the latter may be much increased for a given length of handle by employing the construction according to Figs. 12 to 16. In this construction the hinge portions 43 and 45 which extend through the opening 47 of the rib 7 both leave the same side of that opening to form the body of the handle. As shown in Fig. 12, the wire at the left hand end of the end portion 43 is bent to form a leg portion 49 extending longitudinally of the faster so as to form part of the handle. The wire at the end of this length 49 has a return bend 51, 53, extending the leg to the opposite side of the longitudinal axis of the slide body, the length 53 being symmetrical with the length 49. The length 53 near the rib 7 is reversely bent at 54 and the wire continued to form a leg consisting of lengths 55, 57 and 59 parallel to the lengths 53, 51 and 49, respectively, the length 59 being bent at its end portion to form the hinge portion 45 in the opening 47. At the opposite side of the rib 7 from the length of wire 59 the wire is bent to form a length 61 extending toward the reverse bend 54. Adjacent this reverse bend the length 51 is bent back upon itself at a reverse bend 62 to form a length 63 which terminates in the pin 21.

For closing the space between the reverse bends 54 and 62, and for keeping them in alignment, a bridge piece 67 extends between the two sides of the handle. This bridge piece at one end is bent to form a portion 69 extending about the lengths of wires 49 and 59 at one side of the handle, as shown in Fig. 15, these wires being confined loosely by the bridge piece. At its opposite end the bridge piece is bent to form portions 71 extending into the spaces between the pairs of wires 61, 63 and 53, 55 so that the bridge piece will be maintained in proper position longitudi-

dinally of the handle, the portions 71 loosely connecting the bridge piece to the lengths of wires 63 and 53.

As illustrated in Fig. 14, the opening 47 in the rib 7 may have its outer surface 13 tapered in such way as to provide a larger opening in a vertical direction at the left hand side of the rib as viewed in Figs. 12 and 14 than at the opposite side. This acts to form a better pivot at the ends of the wire portions 43 and 45 adjacent the pin 27 so that a better operation of the latter is secured, and when the handle is swung into fastener closing direction causes the left hand end of the wire portion 45 to be distorted more than the right hand end as viewed in Fig. 12, this causing a twisting as well as a lateral displacement of the wire length 59 and adding to the resiliency of the device.

In making the device according to Fig. 12 the wire forming the handle may be bent to the shape shown, and the portion comprising the pin 27 and lengths 61 and 63 may be passed through the opening 47 with the handle turned at right angles to the slide, the lengths of the other portions being such as to afford sufficient resiliency to permit the necessary springing of the parts during this operation. After the handle is in place the bridge piece 67 may be applied.

The scheme of bending the wire forming the handle according to Fig. 12 may be employed in other shapes of handle as, for example, that shown in Fig. 18, in which there is formed in the opening between the wire lengths 75, 77 and 79, 81 an internal length of wire 83 bent to such shape that the handle is so formed as to provide a preferred gripping means for engagement with the fingers.

It will be understood that, within the scope of the appended claims, wide deviations may be made from the forms of the invention described without departing from the spirit of the invention.

I claim:

1. A slide for a multiple fastener having, in combination, a slide body, a handle for moving said body mounted thereon for swinging about an axis transverse to the direction of movement of said body, locking means for preventing accidental fastener opening movement of said body operated into engaged and disengaged position when said handle is swung in opposite directions respectively, said handle comprising separate relatively resilient parts, cooperating means on said handle and body for forcing said parts to move relative to each other when said handle is swung to a position in which said locking means is released for causing said handle to be urged toward a position in which said locking means is engaged.

2. A slide according to claim 1 in which the relatively resilient parts of said handle and the cooperating means on said handle and body cause the handle to be resiliently retained against any substantial swinging movement from its normal position.

3. A slide according to claim 1 in which the cooperating means on said handle and body force the parts of said handle to move relative to each other only upon the handle being swung in locking means releasing direction a predetermined distance from the extreme end of its arc of travel.

4. A slide according to claim 1 in which the cooperating means on the handle and body force one of said parts to swing a greater distance than

the other when said handle is swung in locking means releasing direction.

5. A slide according to claim 1 in which one of the relatively resilient parts of the handle directly carries the locking means.

6. A slide according to claim 1 in which one of the relatively resilient parts of the handle directly carries the locking means, said parts each having a portion positioned transverse to the direction of movement of the slide body and received in closely adjacent relation in an opening in the slide body, which opening also is positioned transverse to said direction whereby said portions of said parts serve as a pivot for the handle, the walls of said opening cooperating with said portions of said parts to force one of said parts to swing a greater distance than the other when said handle is swung to release the locking means.

20 7. A slide for a multiple fastener having, in combination, a slide body, a handle for moving said body mounted thereon at one side thereof for swinging about an axis transverse to the direction of movement of said body, the handle having a position close to said body with the free end of the handle pointed in the direction of fastener opening movement of said body, a slide lock carried by said handle, which lock is in engaged condition when said handle is in said position and is in released condition when said handle is materially swung therefrom, said handle having a pair of relatively resilient legs positioned longitudinally of said body when said handle is in said position, each leg having a transversely disposed portion received in a transversely disposed opening in said body, said opening being so constructed as to cause the walls thereof to coact with said portions of said legs therein for forcing one leg to swing a greater angular distance than the other when said handle is swung to release said lock.

45 8. A slide according to claim 7 in which the portions of the legs of the handle within the opening in the slide body cause the handle to be resiliently retained against movement when in the first mentioned position of claim 7.

9. A slide according to claim 7 in which the legs are positioned at opposite sides of the longitudinal axis of the slide body.

50 10. A slide according to claim 7 in which the handle is formed of a bent wire of which the legs constitute opposite end portions thereof, the slide lock being an integral part of one of said portions.

55 11. A slide according to claim 7 in which the handle is formed of a bent wire of which the legs constitute opposite end portions thereof, the slide lock being an integral part of one of said portions, the portions of the legs within the opening in the slide body coacting with the walls thereof to cause the handle to be resiliently retained against movement when in the first mentioned position of claim 7.

60 12. A slide for a multiple fastener having, in combination, a slide body, a handle for moving said body mounted thereon at one side thereof for swinging about an axis transverse to the direction of movement of said body, the handle having a position close to said body with the free end of the handle pointed in the direction of fastener opening movement of said body, a slide lock carried by said handle, which lock is in engaged condition when said handle is in said position and is in released condition when said handle is materially swung therefrom, said handle

being formed of a wire bent to form resilient legs at one side of the longitudinal axis of said body with return bends extending them to a reverse bend which joins them at the opposite side of said axis, said legs at the first mentioned side of said longitudinal axis each having a transversely disposed portion received in a transversely disposed opening in said body, which opening is so constructed as to cause the walls thereof to force one of said legs to swing a greater angular distance than the other when said handle is swung to release said slide lock, the transversely disposed portion of one of said legs being bent to form a locking pin constituting said slide lock.

13. A slide for a multiple fastener having, in combination, a slide body, a handle for moving said body mounted thereon at one side thereof for swinging about an axis transverse to the direction of movement of said body, the handle having a position close to said body with the free end of the handle pointed in the direction of fastener opening movement of said body, a slide lock carried by said handle, which lock is in engaged condition when said handle is in said position and is in released condition when said handle is materially swung therefrom, said handle being formed of a wire bent to form resilient legs at one side of the longitudinal axis of said body with return bends extending them to a reverse bend which joins them at the opposite side of said axis, said legs at the first mentioned side of said longitudinal axis each having a transversely disposed portion received in a transversely disposed opening in said body, which opening is so constructed as to cause the walls thereof to force one of said legs to swing a greater angular distance than the other when said handle is swung to release said slide lock, the transversely disposed portion of one of said legs at that side of said longitudinal axis to which said legs are ex-

10 tended having a reverse bend directed toward and terminating adjacent the first mentioned reverse bend, said wire beyond the second mentioned reverse bend having a terminal portion forming a pin constituting said slide lock.

14. A slide for a multiple fastener having, in combination, a slide body, a handle for moving said body mounted thereon at one side thereof for swinging about an axis transverse to the direction of movement of said body, the handle having a position close to said body with the free end of the handle pointed in the direction of fastener opening movement of said body, a slide lock carried by said handle, which lock is in engaged condition when said handle is in said position and is in released condition when said handle is materially swung therefrom, said handle being formed of a wire bent to form resilient legs at one side of the longitudinal axis of said body with return bends extending them to a reverse bend which joins them at the opposite side of said axis, said legs at the first mentioned side of said longitudinal axis each having a transversely disposed portion received in a transversely disposed opening in said body, which opening is so constructed as to cause the walls thereof to force one of said legs to swing a greater angular distance than the other when said handle is swung to release said slide lock, the transversely disposed portion of one of said legs at that side of said longitudinal axis to which said legs are extended having a reverse bend directed toward and terminating adjacent the first mentioned reverse bend, said wire beyond the second mentioned reverse bend having a terminal portion forming a pin constituting said slide lock, and a bridge piece carried by said handle at the portions thereof at opposite sides of said longitudinal axis closing the space between said first and second mentioned reverse bends.

MARTIN WINTERHALTER
